DISPENSER FOR DISPOSABLE NAIL CLEANERS

Jack Marks Granowitz, Danbury, Frank James Marocco, Woodberry, and Gaetano Salvatore Buccino, Bethel, Conn., assignors to American Cyanamid Company, Stamford, Conn., a corporation of Maine

Filed Apr. 2, 1968, Ser. No. 11,262

Term of patent 14 years

Int. Cl. D28—99

U.S. Cl. D86—10

FIG. 1

FIG. 3

FIG. 1 is a side perspective view of the dispenser for disposable nail cleaners, showing our new design;

FIG. 2 is a perspective view of the opposite side of the dispenser for disposable nail cleaners, being fragmentary shown for the purpose of disclosure.

FIG. 3 is a view of the rear of the dispenser for disposable nail cleaners, showing keyhole slots, which may be used for hanging.

The nail cleaners are shown in broken lines in FIG. 2 for illustrative purposes only.

We claim:

The ornamental design for a dispenser for disposable nail cleaners, as shown and described.
